(57) **CLAIM**

The ornamental design for a firearm grip surface with an elongated through-hole aperture, as shown and described.

DESCRIPTION

FIG. 1 is a top, right, front perspective view of the firearm grip surface with a horizontally elongated through-hole aperture.

FIG. 2 is a bottom, right, front perspective view of the firearm grip surface with through-hole aperture of FIG. 1. FIG. 3 is a frontal, elevation view of the firearm grip surface of FIG. 1, the backside being a mirror image thereof; FIG. 4 is a backside, elevation view of the firearm grip surface of FIG. 1, being the mirror image of FIG. 3; FIG. 5 is a top, plan view of the firearm grip surface of FIG. 1;

FIG. 6 is a bottom, plan view of the firearm grip surface of FIG. 1;

FIG. 7 is a left side elevation view of the firearm grip surface of FIG. 1, the right side being a mirror image thereof; FIG. 8 is a right side elevation view of the firearm grip surface of FIG. 1, being the mirror image of FIG. 7; and, FIG. 9 is a top left, perspective view of a the firearm grip surface of FIG. 1 attached to a firearm hand guard showing our new design.

The broken lines showing portions of the design in all figures is included for the purpose of illustrating the environment and unclaimed features and forms not part of the claimed design.
